[57] CLAIM

The ornamental design for a hair braiding tool, as shown and described.

DESCRIPTION

FIG. 1 is a front view of the hair braiding tool showing my new design;

FIG. 2 is a left side view thereof;

FIG. 3 is a right elevational view thereof;

FIG. 4 is a top view thereof; and,

FIG. 5 is a bottom view thereof.

The rear view is a mirror image of FIG. 1.
